UNITED STATES PATENT OFFICE

STANLEY E. MORSE, OF DENVER, COLORADO, ASSIGNOR, BY MESNE ASSIGNMENTS, TO UNION CARBIDE AND CARBON RESEARCH LABORATORIES, INC., OF NEW YORK, N. Y., A CORPORATION OF NEW YORK

DEVICE FOR PRODUCING FLAME REPRESENTATION

Application filed January 23, 1929. Serial No. 334,528.

My invention relates to display devices and more particularly to a device for producing a representation of flame or the like.

It is advantageous wherever possible in advertising to represent a device in actual operation. This will create more interest in the advertising display and will better illustrate the device. In advertising some devices, a working model may be provided to display the device. Other devices, which are impractical to operate, must be provided with means which will represent the operation.

An object of my invention is to provide an action-representing device which may be used in connection with a device to be advertised to give the appearance that the device is in operation.

It is another object of my invention to provide means for producing desirable quivering or pulsation which is present in, for instance, the flame issuing from a lighted torch.

Other objects of my invention reside in the details of construction and will be apparent from a perusal of the following specification, the accompanying drawings and the appended claims.

Referring to the drawings in which my invention is illustrated:

30 Fig. 1 is a front face view of a display sign embodying the features of my invention.

Fig. 2 is a back face view of the left end portion of Fig. 1, showing the vibrating mechanism of the invention.

35 Fig. 3 is a top plan view of Fig. 2, as indicated by the arrow 3 of Fig. 2.

Fig. 4 is a section taken as indicated by the line 4—4 of Fig. 1.

40 For the purpose of illustrating my invention I have shown in Fig. 1 a display board 11, to which an oxy-acetylene welding torch 12 is attached by wire clips 13.

45 Adjacent a cutting tip 14 of the torch 12 is an opening 15 in the board 11. The opening 15 is formed in the shape of a jet of flame issuing from the torch 12. A silken cover 16 is secured to an outer face 17 of the board 11, so as to close the opening 15. Secured to 50 an inner face 18 of the board 11, and also

covering the opening 15 is a sheet of glass 19 which is painted to represent flame.

Mounted on the inner face 18 of the board 11 by brackets 20 is an incandescent lamp 21. The lamp 21 is positioned so that its rays 55 may propagate directly through the translucent cover 16 and painted glass 19 of the opening 15.

Mounted also on the back face 18 of the board 11 below the opening 15 is a vibrating 60 mechanism generally designated by the numeral 22 and hereinafter spoken of as the vibratile member 22, which is construed to mean adapted to or used in vibratory motion. Vibratory is herein defined as meaning of or pertaining to vibration or oscillation; having, consisting of, or causing vibration. The mechanism 22 is wired in circuit, as shown at 23 to a step-down transformer 24 of an ordinary type. The transformer 24 is in turn connected as at 25 to a circuit 26 leading to the lamp 21.

The vibrating mechanism 22 has a base 27 secured to the board 11, which supports a pair of magnets 28 wired in series in the circuit. An armature 29 having a fixed end 30 and a free end 31 is secured, as by a lug 32 on the base 27, in such a position as to be attracted by the magnets 28. A circuit breaker 33, provided with a breaker point 34, is so mounted on the base 27 on the opposite side of the armature 29 from the magnets 28. The armature 29 is adapted to resiliently contact the breaker point 34 and to resiliently oppose attraction by the magnets 28. 85

A flexible member such as a weak coil spring 35 is extended longitudinally across the opening 15, between the opening 15 and the lamp 21. The spring 35 is secured at its upper end by a hook 36 in the bracket 20, and is secured at its lower end by engagement with a hook 37 formed on the outer free end 31 of the armature 29.

The operation of my invention is as follows:

A display sign substantially as that described bearing suitable advertising matter is placed in a desired location and is positioned so as to be viewed by passersby, in 70

an elevation comparable to Fig. 1 of the drawings.

The circuit 26 is then connected with a source of current in any suitable manner. 5 The magnets 28 being energized by an electric current of suitable voltage delivered through the transformer 24 attract the armature 29 downward in the direction of the arrow 38 of Fig. 2, and break the contact between the 10 armature 29 and the breaker point 34. As soon as contact is thus broken, the magnets being no longer energized allow the armature 29 to snap back into engagement with the breaker point 34, which again energizes the 15 magnets 28.

This instantaneous making and breaking of the circuit causes the outer free end 31 of the armature to quickly reciprocate, as indicated by the arrow 39 of Fig. 2, which produces a pronounced vibration of the spring 35, as indicated by the arrow 40 of Fig. 2.

The movement of the spring 35 between the opening 15 and lamp 21 causes the representation of the flame issuing from the torch 12, 25 when viewed as in Fig. 1, to assume a realistic quiver or pulsation, characteristic of such a flame.

Although I have herein shown and described my invention in connection with the 30 reproduction of a flame, it should be understood that numerous other representations and the illusion of movement characteristic of each are easily accomplished by my invention.

35 It should be further understood that although I have herein shown and described only one complete mechanical embodiment of my invention, numerous changes might be made, and many embodiments might be devised by those skilled in the art, without departing from the spirit and scope of my invention.

I claim as my invention:

1. In a display device of the type described, 45 the combination of: a wall having an opening therein; a lamp positioned so as to illuminate said opening; a flexible member extending across said opening; and a vibrating mechanism comprising a pair of magnets connected in series in a circuit, a circuit breaker, and an armature having a fixed end and a free end, said magnets and said circuit breaker being adapted to cause said armature to reciprocate, and said free end of said armature being connected to said flexible member for transmitting a quivering motion thereto, whereby the light rays of said lamp are caused to appear to pulsate.

50 2. In a display device of the type described, the combination of: a wall having an opening therein; a translucent cover closing said opening, said cover having a colored representation thereon; a lamp positioned so as to illuminate said opening; a vibratile member extending across said opening; and mech-

anism associated with said member for transmitting a vibratory motion thereto, whereby said colored representation is caused to appear to pulsate.

3. In a display device of the type described, 70 the combination of: a wall having an opening therein; a translucent cover closing said opening, said cover having a colored representation thereon; a lamp positioned so as to illuminate said opening; a flexible member 75 extending across said opening; and a vibrating mechanism comprising a pair of magnets connected in series in a circuit, a circuit breaker, and an armature having a fixed end and a free end, said magnets and said circuit breaker being adapted to cause said armature to reciprocate, and said free end of said armature being connected to said flexible member, for transmitting a quivering motion thereto, whereby said colored representation 80 is caused to appear to pulsate.

4. In a display device of the type described, 85 the combination of: a wall having an opening therein; a translucent cover closing said opening, said cover having a colored representation thereon; a lamp positioned so as to illuminate said opening; a coil spring having a fixed end secured to said wall and a free end extending loosely across said opening between said lamp and said opening; and mechanism associated with said free end of said coil spring for transmitting a quivering motion thereto, whereby said colored representation 90 is caused to appear to pulsate.

5. In a display device of the type described, 100 the combination of: a wall having an opening therein; a translucent cover closing said opening, said cover having a colored representation thereon; a lamp positioned so as to illuminate said opening; a coil spring having 105 a fixed end secured to said wall and a free end extending loosely across said opening between said lamp and said opening; and a vibrating mechanism comprising a pair of magnets connected in series in a circuit, a circuit breaker, and an armature having a fixed end and a free end, said magnets and said circuit breaker being adapted to cause said armature to reciprocate and said free end of 110 said armature being connected to said free end of said coil spring for transmitting a quivering motion thereto, whereby said colored representation 115 is caused to appear to pulsate.

6. In a display device of the type described, 120 the combination of: a wall having an opening therein; a translucent cover closing said opening, said cover having a colored representation of flame thereon; a lamp positioned 125 so as to illuminate said opening; a coil spring having a fixed end secured to said wall and a free end extending loosely across said opening between said lamp and said opening; and a vibrating mechanism comprising a pair of 130

magnets connected in series in a circuit, a circuit breaker, and an armature having a fixed end and a free end, said magnets and said circuit breaker being adapted to cause said armature to reciprocate and said free end of said armature being connected to said free end of said coil spring for transmitting a quivering motion thereto, whereby said colored representation of flame is caused to appear to pulsate.

7. In a display device of the type described, the combination of: a wall having an opening therein; a lamp positioned so as to illuminate said opening; a vibratile member extending across said opening; and means for vibrating said member, whereby the light rays of said lamp are caused to appear to pulsate.

8. In a display device of the type described, the combination of: a wall having an opening therein; a lamp positioned so as to illuminate said opening; a member capable within itself of vibratory movement extending across said opening; and means for vibrating said member, whereby the light rays from said lamp are caused to appear to pulsate.

9. In a display device of the type described, the combination of: a wall having an opening therein; a lamp positioned so as to illuminate said opening; a member bodily vibratile extending across said opening; and mechanism associated with said member for vibrating the same, whereby the light rays from said lamp are caused to appear to pulsate.

10. In a display device of the type described, the combination of: a wall having an opening therein; a lamp positioned so as to illuminate said opening; a vibratile member having a fixed end secured to said wall and a free end extending loosely across said opening between said lamp and said opening; and mechanism associated with said free end of said member for transmitting a vibratory motion thereto, whereby said light rays from said lamp are caused to appear to pulsate.

11. In a display device of the type described, the combination of: a wall having an opening therein; a translucent cover closing said opening, said cover having a colored representation thereon; a lamp positioned so as to illuminate said opening; a vibratile member having a fixed end secured to said wall and a free end extending loosely across said opening between said lamp and said opening; and means associated with the free end of said member for transmitting a vibratory motion thereto, whereby said colored representation is caused to appear to pulsate.

12. In a display device of the type described, the combination of: a wall having an opening therein; a translucent member covering said opening; an article of merchandise positioned adjacent said opening; a lamp positioned so as to illuminate said member; and means for producing pulsations in the light

rays of said lamp, whereby the illumination on said member pulsates.

13. In a display device of the type described, the combination of: a wall having an opening therein; a translucent member covering said opening; an article of merchandise positioned adjacent said opening; a lamp positioned so as to illuminate said opening; a vibratile member extending between said lamp and said member; and means for vibrating said vibratile member whereby the light rays of said lamp are caused to pulsate.

14. In a display device of the type described, the combination of: a wall having an opening therein; a translucent member covering said opening; an article of merchandise positioned adjacent said opening; a lamp positioned so as to illuminate said member; and means for producing pulsations in light rays of said lamp, whereby the illumination of said member pulsates, simulating a flame issuing from said article of merchandise.

In testimony whereof, I have hereunto set my hand at Manhattan, Kansas, this 12th day of January, 1929.

STANLEY E. MORSE.
